SPIRIT LEVEL

Seymour A. Ostrager, 1188 Grand Concourse,
Bronx, N.Y. 10456

Filed Nov. 6, 1970, Ser. No. 25,851

Term of patent 14 years

Int. Cl. D10—05

U.S. Cl. D52—6

FIG. 1 is a front, end and bottom side perspective view of the spirit level showing my new design; and

FIG. 2 is a front, opposite end and top perspective view thereof; and

FIG. 3 is a fragmentary front elevational view of FIG. 1; and

FIG. 4 is a rear elevational view;

FIG. 5 is a side elevational view taken along the line 5-5 in FIG. 4;

FIG. 6 is an end elevational view taken along the line 6-6 in FIG. 4; and

FIG. 7 is a sectional view taken along the line 7-7 in FIG. 4.

I claim:

The ornamental design for spirit level, substantially as shown.
